(57) **CLAIM**

The ornamental design for a vented plasma cutting electrode, as shown and described.

DESCRIPTION

FIG. 1 is perspective view of a design for a vented plasma cutting electrode.

FIG. 2 is a top view of a design for the vented plasma cutting electrode.

FIG. 3 is a bottom view of a design for the vented plasma cutting electrode.

FIG. 4 is a side view of a design for the vented plasma cutting electrode.

FIG. 5 is another side view of a design for the vented plasma cutting electrode.

FIG. 6 is a further side view of a design for the vented plasma cutting electrode; and,

FIG. 7 is an additional side view of a design for the vented plasma cutting electrode.
